CLAIM

The ornamental design for a safety closure having a lug window, as shown and described.

DESCRIPTION

FIG. 1 is a top perspective view of a safety closure having a lug window according to a preferred embodiment of the present invention;

FIG. 2 is a front view of the safety closure having a lug window according to FIG. 1;

FIG. 3 is a left-side view of the safety closure having a lug window according to FIG. 1;

FIG. 4 is a top view of the safety closure having a lug window according to FIG. 1;

FIG. 5 is a bottom view of the safety closure having a lug window according to FIG. 1; and,

FIG. 6 is a bottom perspective view of the safety closure having a lug window according to FIG. 1.
